(57) **CLAIM**

The ornamental design for a bag hook, as shown and described.

DESCRIPTION

FIG. 1 is a front view of a bag hook showing my new design;

FIG. 2 is a back view thereof;

FIG. 3 is a left-side view thereof;

FIG. 4 is a right-side view thereof;

FIG. 5 is a bottom plan view; and,

FIG. 6 is a top view thereof.

The application relates to the design of a bag hook which is used for attaching items to a golf bag.

The broken lines representing stitching are part of the claimed design.
